MAGAZINE PENCIL WITH SELECTIVELY
USABLE LEADS

Rinaldo Raimondi, Zurich, Switzerland

Application November 12, 1946, Serial No. 709,138
In Switzerland October 1, 1945Section 1, Public Law 690, August 8, 1946
Patent expires October 1, 1965

3 Claims. (Cl. 120—14.3)

1

The present invention relates to magazine pencil with selectively usable leads. Pencils of said type are known, comprising a shaft with a plurality of chambers, each for storing one of the leads and each open towards a barrel having a slot through which a lead may pass from one of said chambers to the pincer for the lead. The pincer may be axially displaced to fix a lead in its working position and to free it to be returned to one of said chambers.

The main object of the invention consists in the provision of a channel arranged between the chambers for storing each a lead and the pincer to hold the lead while being in its position for writing.

A further object of the invention consists in providing simple and effective means to pass the leads from its storing chamber to the pincer by only axially displacing same.

In the accompanying drawing a preferred embodiment of my invention is shown by way of an example. In the drawing:

Fig. 1 is a sectional elevation of a pencil.

Fig. 2 is a side view thereof.

Fig. 3 is a cross section on line 3—3 of Fig. 1.

Fig. 4 is a cross section on line 4—4 of Fig. 1.

Fig. 5 is a cross section on line 5—5 of Fig. 1.

Fig. 6 is a cross section on line 6—6 of Fig. 1.

Figs. 7 and 8 are sections on the line 7—7 of Fig. 1 in different positions of the parts.

Fig. 9 illustrates in a partial sectional view a detail of the pencil.

In a tubular casing 5, which is polygonal in transverse contour, a tubular guide 6 for leading a lead 9 from its storing chamber to its operative position is arranged. The tubular guide 6 carries at its lower end a clamp 2 for a lead having springy prongs, co-operating with a conical bore of the tip of the pencil. To the tubular guide 6 a disc 4 is fastened, which serves as an abutment for a coiled spring 3 supporting the guide 6 and tending to close the clamp 2. To the upper end of the tubular guide 6 a member 22 is fastened acting as a guide while the tubular guide 6 is displaced in axial direction within the casing 5 preventing the rotation of the guide 6. To the latter a rod 21 is fixed to the upper end of which a knob 13 projecting well over the casing 5 is fastened. The lower end 15 of rod 21 is bevelled to guide the lead 9 when the same is brought back from its working position into one of six lead chambers 17 in a magazine barrel 18 rotatably mounted on the rod 21. The chambers 17 are open at their ends, they run in axial direction and receive each but one lead. On the rod 21 a disc 11 is axially displaceable but not rotatably

2

mounted. The disc 11 is provided at its face with teeth and is pressed on to a toothed face of a disc 10 by a coiled spring 12. The disc 10 is axially displaceable within the casing 5. The discs 10, 11 have the same number of teeth as the barrel 18 has chambers 17, that is six. The position of the teeth is such that the face of a chamber 17 coincides with an opening 16 leading to the tube 6 if the teeth of the discs 10, 11 are in full engagement so that a lead 9 may pass from a chamber 17 through the opening 16 into the tube 6. On the barrel 18 a tube 20 is arranged taking part on the rotation of the barrel 18. The tube 20 rests on a small tubular cup 8, the latter being rotatably mounted on the bearing member 22 within the casing 5. The sleeve 8 has a flat bottom and in said bottom the above mentioned opening 16 is arranged which corresponds in shape and in size with the opening of the tube 6 at its upper end. In the casing 5 (Fig. 2) near its upper end, a window opening 19 is arranged, which allows the reading of marks on the knob 13, the marks denoting for instance the kind of lead which is within the chamber ready to be issued and to be brought into its writing position. The cup 8 is provided with a slanting slot 8a into which projects a stud 7 secured to the casing 5. By pressing on the knob 13 in axial direction the cup 8 is moved in axial direction and will be turned to close the upper opening of the tube 6. To prevent a turning of the knob 13 while a lead 9 is in the clamp 2, the knob 13 is made polygonal in cross section to enter the correspondingly shaped upper end of the casing 5, but is provided with a cylindrical lower portion 23 which is the only part of the knob 13 projecting into the casing 5 and permitting a rotation of the knob 13 within the casing 5 when there is no lead in the clamp 2. In such a case the upper polygonal portion of the knob 13 projects above the casing 5 and therefore the knob 13 and therewith the rod 21 and cup 8 may be turned to bring a lead 9 from a chamber 17 into the clamp 2, the pencil being now held by the hand with the tip pointing downwardly. If the knob 13 is now pressed the rod 21 and therewith the guide 6 and the jaws of the clamp 2 are moved downwardly in the casing 5. Moreover the discs 10, 11 are moved downwardly and the tube 20 and the cup 8 are pressed on to the bearing 22 which moves downwardly. The pin 7, which engages the slanting slot in the cup 8 turns the sleeve 8 from the position shown in Fig. 7 to the position shown in Fig. 8 leaving the inlet opening of the tube 6 free to allow the passing of a lead 9, by its own

weight. The lead 9 is led by the slanting wall 14 into the clamp 2.

To release the lead 9 from the clamp and to bring it back into the chamber 17, the pencil is turned upside down. The tip of the pencil is uppermost. By pressing the knob 13 the jaws of the clamp give the lead 9 freedom. The released lead falls by its own weight through the tube 6 downwardly on to the slanting face 15 and enters a chamber 17. By pressing on the knob 13 the cup 8 had been turned in advance by the stud 7 in such a manner that the opening 16 coincides with the opening at the upper open end of tube 6. The lead 9 may pass into the chamber 17. If the pressure on the knob 13 ceases the knob 13 is returned to its initial position by the spring 12 and the cup 8 resumes its position shown in Fig. 8 closing the exit of the guide 6. If there is no lead 9 in the clamp the knob 13 may be turned freely in the casing 5 as only the cylindrical part 23 of the knob 13 projects into the casing 5. The knob 13 may now be turned until another lead arrives in a position to be passed from the chamber 17 to be emptied and may be viewed through the window 19. The positioning of the chambers 17 is effected by turning the knob 13 in combination with the discs 10, 11 by means of which the chambers 17 are brought in true alignment with the tube 6.

What I wish to secure by Letters Patent is:

1. In a magazine pencil with selectively usable leads, a tubular casing provided at one end with a rotatable and axially movable clamping member for a lead, a rotatable and axially movable magazine barrel in said casing and provided with a circular row of axially extending lead chambers, one for each lead, a tubular guide non-rotatably mounted in said casing for guiding leads from any one of said chambers to said clamping member, a cup rotatably mounted at the end of said barrel which discharges the leads into said tubular guide, said cup having a bottom normally closing said lead chambers, but having an aperture adapted to bring any selected lead chamber in said barrel in communication with said tubular guide, manually operable means for rotatably adjusting said barrel to bring the selected lead chamber in alignment with said tubular guide and for axially moving said barrel, and an operative connection between said casing and said cup whereby upon axial movement of said barrel said cup is rotated to move the aperture in its bottom into alignment with the lead chamber which has been moved in alignment with said tubular guide to permit a discharge of the lead from said lead chamber into said tubular guide and vice versa.

2. In a magazine pencil with selectively usable leads, a tubular casing provided at one end with a rotatable and axially movable clamping member for a lead, a rotatable and axially movable magazine barrel in said casing and provided with a circular row of axially extending lead chambers, one for each lead, a tubular guide non-rotatably mounted in said casing for guiding leads from any one of said chambers to said clamping member, a cup rotatably mounted at the end of said barrel which discharges the leads into said tubular guide, said cup having a bottom normally

closing said lead chambers, but having an aperture adapted to bring any selected lead chamber in said barrel in communication with said tubular guide, manually operable means for rotatably adjusting said barrel to bring the selected lead chamber in alignment with said tubular guide and for axially moving said barrel, and an operative connection between said casing and said cup including a pin extending inwardly from the wall of said casing and into a slanting slot provided in said cup, whereby upon axial movement of said barrel said cup is rotated to move the aperture in its bottom into alignment with the lead chamber which has been moved in alignment with said tubular guide to permit a discharge of the lead from said lead chamber into said tubular guide and vice versa.

3. In a magazine pencil with selectively usable leads, a tubular casing of polygonal cross-section provided at one end with a rotatable and axially movable clamping member for a lead, a rotatable and axially movable magazine barrel in said casing and provided with a circular row of axially extending lead chambers, one for each lead, a tubular guide non-rotatably mounted in said casing for guiding leads from any one of said chambers to said clamping member, a cup rotatably mounted at the end of said barrel which discharges the leads into said tubular guide, said cup having a bottom normally closing said lead chambers, but having an aperture adapted to bring any selected lead chamber in said barrel in communication with said tubular guide, a manually operable knob of polygonal cross-section at the other end of said casing for rotatably adjusting said barrel to bring the selected lead chamber in alignment with said tubular guide and for axially moving said barrel, and an operative connection between said casing and said cup whereby upon axial movement of said barrel said cup is rotated to move the aperture in its bottom into alignment with the lead chamber which has been moved in alignment with said tubular guide to permit a discharge of the lead from said lead chamber into said tubular guide and vice versa, said knob having a cylindrical guide portion normally extending into said other end of said polygonal casing and permitting entrance of the polygonal portion of the knob into the casing when a lead is discharged from one of said lead chambers, and means for retaining said polygonal portion of the knob in engagement with said casing for preventing rotation of said knob as long as a lead is held by said clamping member.
